UNITED STATES PATENT OFFICE.

CONRAD NOLDA, OF HASTINGS, NEBRASKA.

AIR-PUMP.

1,332,995.

Specification of Letters Patent.

Patented Mar. 9, 1920.

Application filed December 18, 1917. Serial No. 207,727.

To all whom it may concern:

Be it known that I, CONRAD NOLDA, a citizen of the United States, residing at Hastings, in the county of Adams and State of Nebraska, have invented certain new and useful Improvements in Air-Pumps, of which the following is a specification.

My invention relates to improvements in air pumps of the reciprocatory type.

An important object of the invention is to provide apparatus of the above mentioned character, which is simple in construction, inexpensive to manufacture, highly convenient in use, and will supply an even and continuous volume of compressed air, upon being operated.

Other objects and advantages of the invention will be apparent during the course of the following description.

In the accompanying drawing forming a part of this specification, the figure is a central vertical sectional view through the pump, parts being in elevation.

25 In the drawing, wherein for the purpose of illustration is shown a preferred embodiment of my invention, the numeral 1 designates a base receiving thereon a vertical pump barrel or cylinder 2, having its lower end held within an annular flange 3 of an attaching plate 4. This attaching plate is secured to the base 1, by screws 5 or the like.

Arranged to reciprocate within the barrel or cylinder 2 is a piston 6 of any well known or preferred construction, having connection with a piston rod 7, extending through an opening 8 in a cap 9, suitably secured to the top of the barrel 2, as shown.

40 This cap 9 has an opening or port 10 formed therein, as shown. The piston rod 7 extends upwardly beyond the cap 9 and is rigidly connected with a transverse handle 11.

Disposed upon the base 1, upon one side of the barrel 2 is an air holding tube or cylinder 12, the lower end of which is held within an annular flange 13 of an attaching plate 14, secured to the base 1 by screws 15 or the like. The upper end of the tube 12 is closed by a cap 16 having an air tight connection therewith.

Surrounding the barrel or cylinder 2 are rings 17, preferably clamped thereto by any suitable means, and these rings have connection with arms 18, secured to rings 19,

surrounding the tube 12, and preferably clamped thereto by any suitable means.

Arranged within the lower end or bottom of the barrel 2 is a plug 20, preferably having an air tight fit therein. This plug is provided with a central opening or port 21, the upper end of which is tapered to form a valve seat 22, for an upwardly opening check valve 23. The central port 21 leads 65 into a horizontal port 24, having communication with the atmosphere, as shown. The plug 20 is further provided with a port 25, passing through the top thereof upon one side of the port 21. The lower end of the 70 port 25 is enlarged and also passes through the barrel 2 to receive one end of a pipe 26, as shown.

Arranged within the lower end or bottom of the tube 12 is a plug 27, preferably having an air tight fit therein. This plug is provided with a central port 28, the upper end of which is tapered to provide a valve seat 29, such port passing through the top of the plug. The valve seat 29 is adapted 80 for the reception thereon of an upwardly opening valve 30, or check valve. The opposite end of the port 28 leads into a horizontal port 31, receiving the opposite end of the pipe 26. The numeral 32 designates 85 a port formed in the plug 27, and passing through the top thereof. This port has its opposite end passing through the tube 12, and receives therein a tubular coupling 33, having a flexible hose 34 secured thereto. 90

The operation of the pump is as follows:

Upon the upstroke of the piston 6, the valve 30 remains seated while the valve 23 opens, whereby air passes into the lower end of the barrel 2 through the port 21. Upon 95 the down stroke of the piston 6, valve 23 closes, while valve 30 opens, thereby supplying the compressed air into the holding tube 12. The compressed air is withdrawn from the tube 12, through the hose 34.

Particular attention is called to the fact that all valves are carried by the plugs 20 and 27, disposed in the lower ends of the barrels or cylinders, whereby access may be readily had to the valves, by taking out the 105 plugs, which are of course removable.

It is to be understood that the form of my invention herewith shown and described is to be taken as a preferred example of the same, and that various changes in the shape, 110 size, and arrangement of parts may be re-

sorted to without departing from the spirit of the invention or the scope of the subjoined claim.

Having thus described my invention, I claim:

A pump of the character described, comprising a substantially vertical barrel, a plug arranged in the lower end of the barrel and closing the same, said plug having a 10 centrally disposed vertical opening in its top and a transverse inlet port communicating therewith, a valve seat formed at the top of said opening, a pivoted check valve

arranged within the lower portion of the barrel and disposed on said valve seat, said 15 plug being provided with a vertical outlet opening and a transverse outlet conduit communicating with the outlet opening, and a piston mounted to reciprocate within the barrel above the single valve.

In testimony whereof I affix my signature 20 in presence of two witnesses.

CONRAD NOLDA.
